UNITED STATES PATENT OFFICE.

FREDERIC DORSEY DELLINGER AND SAMUEL H. HUNT, OF WAYNESBOROUGH, VIRGINIA.

IMPROVEMENT IN CAR-TRUCKS.

Specification forming part of Letters Patent No. 118,518, dated August 29, 1871; antedated August 17, 1871.

To all whom it may concern:

Be it known that we, FREDERIC DORSEY DELLINGER and SAMUEL H. HUNT, of Waynesborough, in the county of Augusta and State of Virginia, have invented new and valuable Improvements in Car-Trucks; and we do hereby declare that the following is a full, clear, and exact description of the construction and operation of the same, reference being had to the annexed drawing making a part of this specification, and to the letters and figures of reference marked thereon.

Figure 1 of the drawing is our truck in plan view. Fig. 2 is a vertical section through one wheel and journal-box. Fig. 3 is a side view of the same, the side of the housing for the journal-box being removed; and Fig. 4 is a longitudinal vertical section through one of the journal-boxes.

The nature of my invention consists in the construction and novel arrangement of devices whereby intercalated bearing-rollers are adapted for use in car-trucks to serve as bearings for the journals of the car-axes.

In order to enable others skilled in the art to which our invention appertains to make and use the same, we will now proceed to describe its construction and operation.

A represents the frame of the truck. B B are the axles, and C C the wheels placed on the axles. D D represents boxes or housing inclosing the friction-wheels E E and the ends of the axles. The axle immediately inside of each wheel is surrounded by a collar, a, supported by arms G G from the frame A, and said arms are further braced by braces H H. In each of the boxes D, between the axle and the frame of the truck, are

placed two of the rollers or wheels E. These wheels are made about twice the diameter of the axle, and provided with circular flanges b b a suitable distance apart. These flanges on the two wheels mesh into each other and form the upper bearing for the axle. The journals of the wheels E E are placed in upper boxes d and lower boxes or packing-boxes f, which are fastened together by a central screw-bolt, e, as shown in Fig. 4. These journal-boxes d f are at their ends inclosed by stress-blocks h to resist the diagonal pressure of the rollers. The axle bearing, as above mentioned, against the rollers E E, on its upper side, has a packing-box, I, underneath, resting on the seat-plate, J, which forms the bottom of the housing D. The whole housing D is held together by stirrups i i, as shown in Fig. 2.

Having thus fully described our invention, what we claim as new, and desire to secure by Letters Patent, is—

In a car-truck, the combination with the grooved axle B of the intercalated bearing-rollers E, journal-boxes d f, stress-blocks h, packing-box I, housing D, and the braced adjustable arm G with its terminal collar a, substantially as herein shown and described.

In testimony that we claim the above we have hereunto subscribed our names in the presence of two witnesses.

FREDERIC DORSEY DELLINGER.
SAMUEL H. HUNT.
